UNITED STATES PATENT OFFICE.

MAX MAAG, OF ZURICH, SWITZERLAND, ASSIGNOR OF ONE-HALF TO THE FIRM
MAAG-ZAHNRÄDER & MASCHINEN A.-G., OF ZURICH, SWITZERLAND.

PRECISION FEELER APPARATUS FOR GRINDING MACHINES.

Application filed January 21, 1921. Serial No. 439,011.

To all whom it may concern:

Be it known that I, MAX MAAG, a citizen of the Republic of Switzerland, residing at Zurich, Hardstrasse 219, Switzerland, have invented certain new and useful Improvements in Precision Feeler Apparatus for Grinding Machines; and I do hereby declare the following to be a clear, full, and exact description of the invention, such as will enable others skilled in the art to which it appertains to make and use the same, reference being had to the accompanying drawing, and to letters or figures of reference marked thereon, which form a part of this specification.

Various devices are already known whereby the feed motion of grinding discs may be interrupted or signals operated when a piece has been ground down to a desired degree, this being accomplished by means of a feeler which constantly touches the blank during the operation, thereby nearing the axis of rotation as the blank is ground down until contacts influenced directly or indirectly by the feeler become connected. These usually act by closing one or more electric circuits operating either the above mentioned device for the interruption of the feed motion or the aforesaid signals. The degree of precision of these devices is in many cases insufficient, as the instant of connection of the contacts is to a certain degree uncertain because of the constant application of the feeler against the moving blank. Also because the operation of the mechanical or electrical parts of the interrupting or signal devices cannot be maintained sufficiently uniform, the operation of the said devices takes place either too early or too late. The wear of the feeler constantly applied against the blank constitutes another source of error, as well as the frequently observed corrosion of the contacts arising from sparking caused by vibration due to the constant application of the feeler against the revolving blank, whereby the electric circuit is constantly opened or closed from the first moment of contact until the interrupting or signal device becomes operative.

The present invention relates to improvements in the above mentioned devices, by which the aforesaid disadvantages may be avoided. The feeler according to the invention is not constantly in touch with the blank, but only at certain intervals. For

instance, the feeler may contact with the work for a short moment only after each movement of the grinding disc along the work. It is thus possible to minimize the wear of the feeler and the corrosion of the contacts. According to a further feature of the invention, the circuit which is closed by the connection of the feeler-contacts is not used directly for the operation of the interrupting or signaling device, but serves to operate a relay which in its turn actuates the interrupting or signalling device. The interposition of such a relay causes the mechanical or electrical action which has to be accomplished by the electric circuit closed by the feeler contacts to remain constant. The operation of the signal or interrupting device therefore takes place only at a certain constant intensity of application of the feeler contacts which causes a certain current to flow through the relay circuit and does not depend solely on the actual making and breaking of the connection. The range of the contacts between the first touch and the moment of definite operation of the device is subdivided, whereby the degree of precision of the feeler is correspondingly increased. At the first light touch, the electrical resistance between the contacts is so high that the passage of a current strong enough to actuate the relay is prevented. The said resistance decreases rapidly, however, with the increasing intensity of application and allows more current to pass. The relay is not actuated until the pressure between the contacts is sufficient for a certain current to pass.

The relay enters into action sooner or later according to force necessary to move it. In order to grind down various similar blanks exactly to the same degree, it is necessary that the force to actuate the relay should remain constant, so that an equally strong current is each time necessary to actuate it, and therefore the respective positions of the feeler contacts must also be exactly the same.

The fundamental idea of the invention, according to which the blank is only touched from time to time for a short moment in combination with a relay actuated by an exactly determined mechanical force can of course be realized in many different ways.

The accompanying drawings show an example of a precision feeler according to the

present invention, in which the feeler, which is normally maintained at a distance from the blank, is periodically brought towards the latter by means of a solenoid each time the blank has passed the grinding disc and is released immediately after touching it. The force necessary to actuate the relay is maintained constant by means of an inclined flap rotatably mounted about its lower edge, which flap has to be swung over its dead point by means of a small magnet disposed in the circuit of the feeler contacts, whereupon the said flap in tilting forward closes another circuit actuating the interrupting 10 or signalling device.

The accompanying drawings show by way of example an arrangement of this kind, in which two contacts are provided, the two electric circuits actuating relays each of which serves respectively to operate one flap of constant resistance whereby further circuits are closed which light up signal lamps.

In these drawings:

Fig. 1 is a section through the feeling device with signal apparatus and support.

Fig. 2 shows the device seen from above, partly in section;

Fig. 3 is a view of the signals;

Fig. 4 illustrates in a diagrammatic manner a perspective view of the device showing the electric connections;

A support 1 on which the parts of the feeler mechanism are mounted is fixed to the work carrying table of the grinding machine so that the end of a feeler bar or rod 4 may contact with the work being ground. With each reciprocation of the work and table past the wheel, a contact 62 on the table touches a corresponding contact on a lever 61 so that the solenoid of the feeler device is momentarily energized.

The support 1 carries two outer casings 2 and 3 of which the first contains the feeling device with the electric contacts and the solenoid, and the second the relays and signal device. The outer head 6 of the feeler 4 is pressed at certain intervals against the blank 7, by energizing the solenoid thereby compressing the light spring 8, which serves to return the feeler to its initial position away from the blank as soon as the current traversing the solenoid is interrupted. The feeler is slidably mounted in sleeves 9 and 10 carried in the casing and is fitted with a piston 11 co-operating with the casing cylinder 12 so as to form an air cushion, absorbing any shocks due to the movement of the feeler. The feeler rod is fitted with a cross piece 13 on which the two contacts 14 and 15 are attached by means of differentially adjustable micrometer screws 16 and 17. The opposing contacts 22 and 23 are insulated in the support 1. Contact 22 is displaceable against the action of a spring 27. The contact carrier 26 is pressed against nut 29

by means of spring 27 and plate 28, and is pushed back resiliently by the movement of the feeler after touching the contacts. Contacts 14 and 22 are so-called pre-contacts, 15 and 23 the final contacts, they are preferably adjusted in such a manner that the pre-contacts touch 1/100 mm. before the final contacts.

A perfectly air tight movable rubber sleeve 30 is interposed between the feeler and the casing, so as to prevent water or grinding dust from entering the casing 2. The feeler is fitted at its front end with a flat diamond 31. The solenoid coil 5 is situated inside the soft iron casing 32 attached to the outer casing 2, and when energized it exerts an attractive force on disc 33 fixed to the feeler rod 4. The spring 8 is supported against disc 34 which closes the casing 32. All parts are enclosed in the dust-proof hood 18. The two relays 40 and 41 with signal lamps 42 and 43 and flaps 44 and 45 are disposed inside casing 3 situated below casing 2. One of the two flaps is provided for the pre-contact, the other for the final contact. A lever 46 or 47 respectively rotatably mounted on pivot 48, is situated between each relay and flap, one end of said lever being attracted by the relay when the circuit is closed, the other end fitting the somewhat inclined flap in such a manner that the latter tilts over its upper dead point and falls on to contact 50 or 51 respectively, thus establishing a circuit through lamp 42 or 43 respectively, the signal being rendered visible by the falling over of the flap.

When the blank is sufficiently ground, the solenoid circuit is interrupted by means of switch 61 (Fig. 4) being out of contact with contact 62, spring 8 then returns the feeler 4, and pre- and final-contacts are separated from each other thus interrupting the relay circuits so that the levers 46, 47 are respectively drawn back by springs 52, 53. The flaps can then be recocked by means of milled knobs 54 and 55 thus breaking the lamp circuit after which the device is in position for operating upon another blank of the same size as the first.

The perspective view of Fig. 4 shows the electric circuits. Conductor 64 is led from the battery 60 over switch 61, actuated by the reciprocating slide of the machine, to contact 62, then through coil 5 of the solenoid, to fixing screw 63, which clamps the end of this conductor to casing 32.

The casings 32, 2 and 3 (Figs. 1 and 2) are connected electrically together by the metallic support 1 and to battery 60 by conductor 65.

Four sub-circuits are arranged in parallel with the main circuit. One of these goes from the battery through relay 40, pre-contact 22, 14 and through casing 2 and conductor 65 back to the battery, whilst the other

goes through relay 41 and final contacts 23 and 15. The third and fourth subcircuits go from the battery through the signal lamps 42, 43 respectively, contacts 50, 51 respectively, flaps 44, 45 respectively and through casing and conductor 65, back to the battery.

To initially set the feeler mechanism in co-operative position on a standard form of 10 cylindrical grinding machine, a blank or gage of the predetermined finished dimension to be ground is placed in operative position on the work supporting means of the grinding machine and the feeler diamond 31 on the 15 feeler rod 4 moved to engage the cylindrical surface of this gage. This movement of the feeler mechanism may be accomplished by means of adjusting screws which preferably are of the form disclosed in my co-pending application 439,012, filed on even date herewith. The contact carrying lever 20 61 is then manually moved to close contact with the member 62 so that an electric circuit is formed continuously energizing the 25 solenoid 5. This holds the feeler diamond 31 in its extreme position toward the work axis. By positioning the body member of the feeler mechanism by adjustment of the 30 positioning screws as above indicated, the mechanism may be set so that the final contact between members 15 and 23 is closed at any predetermined diameter at which point the mechanism is in position for operation upon blanks of the same size as that used as 35 a gage.

With the feeler mechanism adjusted as above described, the grinding operation may be started by traversing the tool past the work which preferably may be done by 40 means of traversing the slide on which the contact member 62 is mounted. As this slide is reciprocated so that the part of the work to be ground is traversed past the wheel or grinding disc, the contacts 62 and 61 are 45 momentarily closed by this movement of the slide in each direction. This traversing movement of the work past the grinding disc therefore momentarily energizes solenoid 5 and thus moves the feeler diamond 31 toward the work, after which the contact 50 between members 61 and 62 is opened by further movement of the slide at each time the spring 8 withdraws the diamond 31 from engagement with the rotating work.

55 This momentary energizing of the solenoid 5 advances the feeler diamond 31 toward the work and as long as the work being operated on is above its predetermined size and for which the mechanism is adjusted the 60 relay circuits including the solenoids 40 and 41 are not energized and therefore the signals 42 and 43 are not operated. As soon as the grinding has proceeded to such 65 a point that the work is almost ground to its final predetermined size, movement of

the feeler rod 4 and its diamond 31 is sufficient to close the contact between members 14 and 22. This operates one of the relay circuits including the solenoid 40 and also operates the signal 42. Further reciprocatory movement of the slide and continued grinding reduces the size of the work still further until it is down to its final precise dimension. At that point the movement of the feeler rod 4 not only closes the contact 75 between members 14 and 22 but also closes contact between members 15 and 23. This final contact closes the relay circuit including the solenoid 41 and thus operates the signal 43 thus advising the operator that the 80 grinding operation has been completed, after which the work may be removed and a new blank inserted in position.

I claim:

1. A precision feeler apparatus for grinding machines, in combination, an electric circuit, means adapted to close said circuit at each reciprocation of the work carrying slide of a grinding machine, a feeler mechanism, means to momentarily advance said 90 feeler mechanism toward the work, relay circuits, means adapted to close said circuits when the movement of the feeler exceeds a predetermined amount, and independent signals successively operated by 95 the closing of said relay circuits.

2. A precision feeler apparatus for grinding machines, in combination, an electric circuit, means adapted to close said circuit at each reciprocation of the work carrying slide of a grinding machine, a feeler mechanism, means to momentarily advance said 100 feeler toward the work, two independent relay circuits, means adapted to close said circuits, when the movement of the feeler exceeds predetermined different amounts, 105 and signals separately and successively operated by the closing of each of said relay circuits.

3. A precision feeler apparatus for grinding machines, in combination, a feeler rod, means adapted to advance said rod toward the work being ground, relay circuits, means adapted to close said circuits by movement of said feeler more than predetermined 110 amounts, and signals successively operated by the closing of said relay circuits.

4. A precision feeler apparatus for grinding machines, in combination, a feeler rod, means adapted to advance said rod toward the work being ground, independent relay 120 circuits, means adapted to close said circuits by movement of said feeler rod more than predetermined different amounts, and signals separately and successively operated by 125 the closing of each of said relay circuits.

5. A precision feeler apparatus for grinding machines, in combination, a feeler, means adapted to advance said feeler into contact with the blank for a short time at 130

certain intervals, a relay, means adapted to actuate said relay by a constant force, said relay being actuated by electric means upon movement of the feeler, and a signal device actuated by the relay and electrically connected to the latter.

6. A precision feeler apparatus, in combination, a feeler of the rod type, means adapted to momentarily advance said feeler into contact with and away from the blank at certain intervals, a solenoid, means to energize said solenoid to effect the movement of the feeler rod towards the blank, a spring operatively connected to the feeler rod and effecting the movement of the latter away from the blank, an air damper operatively connected to the feeler rod, a relay, means adapted to actuate said relay by a constant force, said relay being actuated upon movement of the feeler, and a signal device actuated by the relay and electrically connected to the latter.

7. A precision feeler apparatus, in combination, a feeler displaceably arranged in its axial direction, means adapted to bring said feeler into contact with the blank for a short time at certain intervals, a solenoid adapted to effect the movement of the feeler towards the blank, a spring operatively connected to said feeler and adapted to effect the movement of the latter away from the blank, a relay adapted to be actuated by a constant force, a switch operated by parts of the machine tool on which the blank is machined, a contacting device actuated by the feeler, a signal lamp, a hinged flap actuated by said relay, a source of electricity, an electric main circuit between the source of electricity, said switch and said solenoid, an electric sub-circuit connected in parallel to said main circuit and comprising said source of electricity, said relay and said contacting device, and an electric sub-circuit arranged in parallel to said main circuit and comprising said source of electricity, said signal lamp and said flap.

8. A precision feeler apparatus, in combination, a feeler displaceably arranged in its axial direction, means adapted to bring said feeler into contact with the blank for a short time at certain intervals, a solenoid adapted to effect the movement of said feeler towards the blank, a spring operatively connected to said feeler and adapted to effect the movement of the latter away from the blank, a final contact device operated by said feeler, a pre-contact device operated by said

feeler, a relay electrically connected to the final contact device, two independent signal devices, means operated by the first mentioned relay and electrically connected to one signal device, and second means operated by the second relay and electrically connected to a second signal device.

9. A precision feeler apparatus, in combination, a feeler displaceably arranged in its axial direction, means adapted to bring said feeler into contact with the blank for a short time at certain intervals, a solenoid adapted to effect the movement of said feeler towards the blank, a spring operatively connected to said feeler and adapted to effect the movement of the latter away from the blank, adjustable contact devices operatively connected to said feeler, a casing inside which the aforementioned parts are mounted, relays electrically connected to said contact devices, hinged flaps adapted to be tilted by means operated by said relays, signal lamps, contacts interposed between said flaps and said lamps and closed by the tilted flaps, and a second casing in which said relays, flaps, signal lamps and contacts are arranged.

10. A precision feeler apparatus, in combination, a feeler displaceably arranged in its axial direction, means adapted to bring said feeler into touch with the blank for a short time at certain intervals, including a solenoid adapted to effect the movement of said feeler towards the blank, a spring operatively connected to said feeler and adapted to effect the movement of the latter away from the blank, an adjustable final contact device operated by said feeler, an adjustable pre-contact device operated by said feeler, said two contact devices being so adjusted relatively to each other, that the pre-contact device is actuated at the beginning of the last step of machining the blank and the final contact device at the finish of said step, a relay, means connecting said relay electrically to the final contact device, a second relay, means connecting said relay electrically to the pre-contact device, a first signalling device operated by the first mentioned relay, and indicating the finish of the machining of the blank, a second signalling device operated by the second relay and indicating the last step of machining the blank.

In testimony that I claim the foregoing as my invention, I have signed my name.

MAX MAAG.
